(57) **CLAIM**

The ornamental design for a reagent container, as shown and described.

DESCRIPTION

FIG. 1 is a perspective view of a reagent container showing the new design;

FIG. 2, FIG. 3, FIG. 4 and FIG. 5 are side views thereof;

FIG. 6 is a top view thereof; and,

FIG. 7 is a bottom view thereof.

The broken lines in the drawings depict portions of the reagent container that form no part of the claimed design.
